GAUGE LAPPING MACHINE

Alden M. Drake, West Hartford, Conn., assignor to
 Niles-Bement-Pond Company, West Hartford,
 Conn., a corporation of New Jersey

Application June 27, 1944, Serial No. 542,288

11 Claims. (Cl. 51—64)

1

This invention relates to lapping machines and particularly to a machine for lapping gauging surfaces such as those of an adjustable snap gauge having opposed flat parallel work engaging surfaces.

More in particular the invention relates to a lapping machine for flat parallel surfaces including means for mechanically holding a work piece in position with its surfaces being lapped in contact with opposed flat parallel faces of a lapping member, the lapping member being actuated while the work piece is free to adjust itself relative to the lapping surfaces, and the work piece being actuated relative to the lapping surfaces while being free to adjust itself relative to the lapping member.

Another object of the invention is to provide means for actuating a lapping member having opposed flat parallel faces, these movements being in a direction transverse to its longitudinal axis while permitting the lapping member to adjust itself angularly about its longitudinal axis.

Another object of importance is to provide means for actuating the work piece relative to the lapping member in a direction parallel to the longitudinal axis of the lapping member while permitting the work piece to adjust itself to bear uniformly throughout its surfaces being lapped against the lapping surfaces and to oscillate about an axis normal to the surfaces being lapped.

And finally it is an object of the invention to provide means for adjusting the gauging surfaces of the work piece being lapped relative to the lapping member during the lapping operation.

With the above and other objects in view the invention includes the features of construction and operation set forth in the following specification and illustrated in the accompanying drawings.

In the accompanying drawings annexed hereto and forming a part of this specification, I have shown the invention embodied in a machine for lapping the gauging surfaces of an adjustable gauge adapted particularly for gauging the diameters of plain cylindrical parts, but it will be understood that the invention can be otherwise embodied and that the drawings are not to be construed as defining or limiting the scope of the invention, the claims appended to this specification being relied upon for that purpose.

In the drawings:

Figure 1 is a front elevation of the principal

2

parts of a lapping machine made in accordance with the present invention and showing a standard form of adjustable snap gauge in position for lapping operations upon its gauging surfaces.

Fig. 2 is a view of a portion of the mechanism shown in Fig. 1 upon an enlarged scale and sectioned to more clearly disclose the means for adjusting the parts of the work piece being lapped.

Fig. 3 is a horizontal sectional view through the work piece adjusting means shown in Fig. 2.

Fig. 4 is another view shown in side elevation of the clamping and adjusting means for the parts having their gauging surfaces lapped.

Fig. 5 is a detail mechanism forming part of the work restraining or positioning means during its actuation.

Fig. 6 is a side elevation in section of the actuating and mounting mechanism for the lapping member.

Fig. 7 is a front elevation of the parts shown in Fig. 6.

Fig. 8 is a detail sectional view taken on the plane of line 8—8 shown in Fig. 6, and

Fig. 9 is a plan view of the work holder taken on the plane of line 9—9 in Fig. 1.

In the above-mentioned drawings there has been shown but one embodiment of the invention which is now deemed preferable, but it is to be understood that changes and modifications may be made within the scope of the appended claims without departing from the spirit of the invention.

Briefly, and in its broadest aspect, the invention may include the following principal parts: First, a base; second, a horizontal spindle preferably adapted to be rotated at any appropriate speed; third, an eccentric on the forward end

40 of the spindle adapted to engage a horizontally slidable shoe mounted within a vertically movable slide so that rotation of the spindle and eccentric will reciprocate the slide vertically a short distance; fourth, a lap holding member

45 mounted within this vertical slide and preferably adjustable laterally with minimum friction; fifth, a lap mounted in this laterally movable member freely rotatable about its longitudinal axis; sixth, a reciprocating arm actuated hydraulically or

50 otherwise in a direction parallel to the longitudinal axis of the lapping member; seventh, a bracket secured to the outer end of said arm and having an opening therein extending horizontally in a direction normal to the direction of movement of said arm; eighth, a yoke member

55

having a lateral extension engaging within the opening in the bracket; ninth, resilient means retaining the yoke substantially in a vertical plane but permitting limited oscillatory movement about the axis of the projection; tenth, a second yoke engaging the first yoke for oscillating movement about a substantially vertical axis; eleventh, work holding members within the second yoke member; and twelfth, means within the second yoke member for adjusting the parts of the work piece being lapped toward and from the lapping surfaces of the lap.

The embodiment of the invention illustrated is for lapping the work engaging surfaces of an adjustable snap gauge. These surfaces after the gauge has been completely assembled, are required to be finished to an extreme precision as to parallelism and flatness. Heretofore this operation has been accomplished by hand with a fixed lapping member by moving the gauge over the surfaces of the lap. The present machine enables this operation to be accomplished mechanically, quickly and to a high degree of parallelism.

Referring more in detail to the figures of the drawings, it will be seen that the drawings disclose a machine for actuating a lap having opposed flat parallel surfaces while permitting adjustment of the lap angularly about its longitudinal axis, there also being work supporting and actuating means associated therewith. The mechanism for operating the lapping member will first be described.

By reference first to Fig. 6 it will be seen that a horizontal extending spindle 10 is rotatably mounted within a base 11. Preferably this spindle 10 may be rotated by a hydraulic variable speed device either continuously or alternately in opposite directions. As the means for rotating this spindle form no part of the present invention, further description of this rotating means and its control is not thought to be necessary. At the forward end of this spindle 10 is an eccentric 12 extending centrally within a bearing shoe 13 movable horizontally within a slide 14 which in turn is vertically movable on suitable ways provided on the front face of the base. Laterally movable relative to the vertical slide 14 is a horizontal slide 15 mounted within the vertical slide. From the above described mechanism it will be seen that the horizontally movable slide 15 will be reciprocated vertically with the vertically movable slide 14 but will be free to adjust itself laterally during this vertical reciprocatory movement.

Within the horizontally movable slide 15 is a lap holding member 16 preferably mounted for rotation upon anti-friction bearings about a horizontal forwardly extending axis that is parallel to the spindle 10. Retained in this holder 16 by any preferred means permitting convenient mounting and demounting is a lapping member 17. In the embodiment of the invention shown in the drawings the lapping member 17 is in the form of a rectangular rod, opposite sides of which form the lapping surfaces. This rod 17 extends horizontally, is free to adjust itself laterally and angularly about its longitudinal axis, and is reciprocated by the vertical slide 14 and eccentric 12 in a vertical plane.

The means for actuating the work piece W relative to and during actuation of the lapping member 17 comprise a piston 20 shown in Fig. 1 which may be reciprocated hydraulically or otherwise in a direction parallel to the axis of

the lapping member 17. As the operating mechanism for this piston forms no part of this invention, further description is not thought necessary. At the forward end of this piston is a laterally extended bracket 21 secured thereto and having a transverse horizontal opening extending therethrough. The bracket 21 at the free end of the piston or ram 20 is secured thereto in fixed position but is free to be angularly adjusted with the piston 20 about its axis. A forwardly extending bar 22 is provided in the base extending parallelly to and at one side of the piston 20 against which a roller 23 on the bracket 21 may ride. This engagement of the roller 23 with the rod or bar 22 keeps the bracket 21 in position to support yoke members, presently to be described, in position to engage the work piece W with the lapping member 17. When not in use, however, the bracket 21 may be swung to an angularly inoperative position for changing the yokes or to mount other types of work pieces.

The transverse opening in the bracket 21 forms a bearing for a yoke 24 having upper and lower extending arms 25 and 26, respectively, adapted to retain another yoke member 27 therein. The yoke 24 has an extension 28 entering the opening in the bracket or arm 21 about the axis of which the yoke member 24 may oscillate. As shown in Figs. 1 and 9, arms 25 and 26 are or may be integral with the central portion of yoke 24. Arms 29 and 30, which may form a unitary member, are pivotally mounted relative to arms 25 and 26 and are resiliently held toward their closed position relative to arms 25 and 26 by a spring 31 pressing plunger 31a against the central portion of the member forming the arms 28 and 29.

In order to resiliently retain the first yoke member 24 in substantially vertical position during reciprocatory movements of the bracket 21 the yoke 24 has an arm 32 extending laterally and horizontally above the axis of its horizontal extension 28. The end of this arm 32 engages between two spring pressed plungers 33 mounted in the bracket 21. The yoke member 24, therefore, is constrained to remain in a substantially vertical position but may oscillate against the pressure of light springs engaging plungers 33, the pressure of which may be adjusted by screws 34, forcing the plungers 33 together against opposite sides of the arm 32.

The second yoke member 27 referred to above and which has its upper and lower extension 35 disposed between the arms 25 and 26 of the first yoke member 24 on one side and arms 29 and 30 on the opposite side is adapted to have a work piece W clamped substantially centrally therein. As the clamping members may be of any approved form, it is not thought that further description of them is necessary.

Mounted on this second yoke member 27 are adjusting and clamping means for the adjustable gauging members 36 of the work piece W, the work engaging surfaces of which are being lapped. The particular embodiment of the invention described in the drawings is a snap gauge for plain cylindrical members, there being a single anvil 37 along one side of the frame and two independently adjustable anvils or gauging members 36 on the opposite side. The opposed surfaces of the single anvil 37 and the opposed adjustable anvils 36 have flat parallel faces which are the surfaces lapped in this lapping machine and form the gauging or work engaging surfaces of the snap gauge W.

In order to effect these adjustments of members 36 during the lapping operation screw driver members 40 are mounted within the second yoke member 27, two of which engage the slotted ends of the adjusting screws 41 for the anvils 36 and the other two engage the ends of the clamping screws 42 for these anvil members. These screw driver members 40 are slidably mounted within portions of the yoke 27 and are normally pressed toward their anvil engaging positions by light 10 springs 43. Hand levers 44 are provided for the screw driver member 40 engaging the adjusting and clamping screws 41 and 42 so that these members 40 may be quickly withdrawn from engagement whenever desired.

To rotate these screw driver members 40 to unclamp, adjust, and reclamp the anvils 36, gears 45 are provided on these members 40 in mesh with elongated idlers 46 which in turn are engaged by other pinions 47 on shafts 48 rotatable manually by handles extending to the outside of the yoke member 27. By means of the pinions 45-46 and 47 and the location of their supporting shafts the handles 49 are spaced apart for convenient operation.

In operation the lapping member 17 is reciprocated in a vertical plane and with the work piece W mounted in yoke 27, as shown, the bracket 21 is reciprocated horizontally in the direction of the axis of the lapping member. This movement induces a swinging movement of the yoke 27 and yoke 24 about the axis of the extension 28. This swinging movement is due to the fact that the support and operating connection for the yoke 24, that is the extension 28, is a material distance above the axis of the lapping member. Also the lapping member 17 can freely adjust itself laterally and angularly about its axis. In addition the yoke 27 can swing about the axis of its upper and lower extensions 35.

The result of these movements and adjustments is to permit the surfaces of anvils 36 and 37 being lapped to bear evenly upon the surfaces of the lapping member 17. The pressure of these surfaces against the lapping member 17 may be adjusted during operation by means of the screw driver members 40 engaging the adjusting and clamping members 41 and 42 for the anvils 36. In this manner and with a lapping compound applied to the member 17 lapping can be continued until opposite flat parallel surfaces are obtained on the anvils 36 and 37.

What I claim is:

1. A lapping machine comprising in combination, mechanism for reciprocating a lap having flat parallel lapping surfaces, means providing adjustment of said lap in a direction normal to its direction of movement, means for actuating a work piece having opposed parallel surfaces over the surfaces of said lap in a direction parallel to said lap, means supporting the work piece with the surfaces being lapped contacting opposite surfaces of said lap, and means providing lateral adjustment of said work piece relative to said lap, whereby said work piece may adjust itself to the surfaces of said lap during lapping movements of said work piece and lap.

2. A lapping machine comprising in combination, mechanism for reciprocating a lap having flat parallel lapping surfaces, means providing adjustment of said lap angularly about its axis and in a direction normal to its direction of movement, means for actuating a work piece having opposed parallel surfaces over the surfaces of said lap in a direction parallel to said lap

5 while said lap is being reciprocated, means supporting the work piece with surfaces being lapped contacting opposite surfaces of said lap, and means providing lateral adjustment of said work piece relative to said lap, whereby said work piece may adjust itself to the surfaces of said lap during lapping movements of said work piece and lap.

3. A lapping machine comprising in combination, mechanism for reciprocating a lap having flat parallel lapping surfaces, means providing adjustment of said lap in a direction normal thereto, means for actuating a work piece having opposed parallel surfaces over the surfaces of said lap in a direction parallel to said lap while said lap is being reciprocated, means supporting the work piece with surfaces being lapped contacting opposite surfaces of said lap, and means effecting oscillatory movements of said work piece relative to said lap during the lapping operation, whereby said work piece may adjust itself to the surfaces of said lap during lapping movements of said work piece and lap.

4. An operating mechanism for the lapping member of a lapping machine comprising a rotatable spindle having an eccentric at one end, a slide reciprocated thereby in a vertical plane normal to the axis of said spindle, a second slide mounted within said first mentioned slide for free movement in a plane at right angles to the plane of movement of said first slide, and a lapping member having opposite plane parallel lapping surfaces mounted in said second slide for free rotary movement about its longitudinal central axis.

5. Work supporting and actuating means for a lapping machine comprising in combination, a yoke member having a projection extending laterally therefrom, actuating means engaging said projection for reciprocating said yoke member, a second yoke supported for oscillatory movements about an axis normal to the reciprocatory movements of said first yoke member, and work clamping means within said second yoke.

6. Work supporting and actuating means for a lapping machine comprising in combination, a yoke member having a projection extending laterally therefrom, actuating means engaging said projection for reciprocating said yoke member while permitting oscillatory movements thereof, a second yoke supported by said first yoke for oscillatory movements about an axis normal to the oscillatory movements of said first yoke member, and work clamping means within said second yoke.

7. Work supporting and actuating means for a lapping machine comprising in combination, a yoke member having a projection extending laterally therefrom, actuating means engaging said projection for reciprocating said yoke member in a direction normal to said projection, a second yoke supported by said first yoke member for oscillatory movements about an axis normal to the reciprocatory movements of said first yoke member, and work clamping means within said second yoke.

8. Work supporting and actuating means for a lapping machine comprising in combination, a yoke member having a projection extending laterally therefrom, actuating means engaging said projection for reciprocating said yoke member horizontally while permitting oscillatory movements of said yoke member about said projection, a second yoke supported by said first yoke member for oscillatory movements about an axis

normal to the oscillatory movements of said first yoke member, and work clamping means within said second yoke.

9. Work adjusting means for a lapping machine comprising in combination, a yoke member, means to reciprocate said yoke member while permitting angular adjustments thereof, clamping means within said yoke member for a work piece, and means mounted within said yoke member for advancing a part being lapped toward a lapping member during the lapping operation.

10. Work adjusting means for a lapping machine comprising in combination, a yoke member, means to reciprocate said yoke member while permitting angular adjustments thereof, clamp- 15

ing means within said yoke member for a work piece, and means mounted within said yoke member for adjusting a part of the work piece being lapped toward the lapping surface of the lapping member during the lapping operation.

11. Work adjusting means for a lapping machine comprising in combination, a yoke member, means to reciprocate said yoke member while permitting angular adjustments thereof, clamping means within said yoke member for a work piece, means mounted within said yoke member for adjusting a part being lapped toward the lapping member during the lapping operation, and means to clamp and unclamp said part.

ALDEN M. DRAKE.
